HARRY MAURUS, OF NEW YORK, N. Y., ASSIGNOR TO DUPLAN SILK CORPORATION, OF NEW YORK, N. Y., A CORPORATION OF DELAWARE

DESIGN FOR A TEXTILE FABRIC

Application filed October 15, 1931. Serial No. 41,401. Term of patent 3½ years.

To all whom it may concern:

Be it known that I, HARRY MAURUS, a citizen of the United States, residing at 60 West 76th Street, in the borough of Manhattan, city of New York, county of New York, and State of New York, have invented a new, original, and ornamental design for a Textile Fabric, of which the following is a specification, reference being had to the accompanying drawing, forming part thereof.

The figure is a plan view of a textile fabric, showing my new design.

The dot and dash lines on the drawing outline the design unit, which unit is repeated in regular succession, as indicated by the extensions beyond the unit boundaries.

I claim:

The ornamental design for a textile fabric substantially as shown and described.

HARRY MAURUS.
